(57) **CLAIM**

The ornamental design for a ladder latch as shown and described.

DESCRIPTION

FIG. 1 is a perspective view of a ladder latch showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the ladder latch where the ladder latch is in a configuration of use.

The broken lines in FIG. 9 showing a ladder depict environment and form no part of the claimed design. The other broken lines in the drawings depict portions of ladder latch and form no part of the claimed design.
